UNITED STATES PATENT OFFICE.

MATTHEW HAWE, OF NEW YORK, N. Y.

DETACHABLE SOLE.

SPECIFICATION forming part of Letters Patent No. 333,126, dated December 29, 1885.

Application filed May 8, 1885. Serial No. 164,743. (No model.)

To all whom it may concern:

Be it known that I, MATTHEW HAWE, a citizen of the United States, residing at the city of New York, in the county of New York and State of New York, have invented certain new and useful Improvements in Detachable Soles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to detachable soles for boots or shoes; and the novelty consists in the construction, arrangement, and adaptation of parts, as will be more fully hereinafter set forth, and specifically pointed out in the claims.

It is well known that rubber extending over the upper of a boot or shoe not only injures the leather of the upper, but heats, sweats, and draws the feet of the wearer.

It frequently happens in large cities that for successive cloudy days the sidewalks and crossings are wet and covered with a black mud, even though no large quantity of rain falls in the meantime. Upon such and other occasions it is desirable to have a detachable rubber sole—one which will only engage and protect the sole upon the ball of the foot, and which may be readily applied and taken off. While sandals are aimed at such a purpose, they partly cover the upper and would destroy the polish of a fine boot, besides the more serious faults hereinbefore mentioned. It is desired to produce a detachable sole which will not in any sense touch or interfere with the upper—one which for short outdoor trips may be put upon the foot without even affecting a fine polish, one which will protect fine shoe-leather from permeating dampness, and which may be readily applied. I provide such a sole. I provide an upwardly-extending elastic flange which will clamp the sole only of the boot by its inherent spring action, and only that portion of the sole which is forward of the shank or instep. I provide

means for clamping the sole to the shank of the boot to hold it well back, and I provide

means for maintaining a proper tension upon the elastic flange.

My invention is illustrated in the accompanying drawings, which form a part of this specification, and in which—

Figure 1 is a perspective view of the device, Fig. 2 a transverse section, and Fig. 3 a bottom plan.

Referring to the drawings, A designates the detachable sole of rubber, having a roughened bottom, a, and an upwardly-extending edge flange, a', with bead a''. This flange inclines inwardly when the material is in a normal state, but is elastic, and may be readily stretched over the edges b of a boot-sole, B. When thus passed over the edges of a boot-sole and released, the flange will spring inward and securely clamp the projecting sole. The rear portion of the sole inclines upward to correspond with the contour of ordinary foot-wear, and upon the upper inner surface of this portion I apply a spring-clamp, C, having hooked ends or sides c, which are designed to engage the edges of the sole in the shank of the boot.

In applying the detachable sole the toe of the boot is inserted between the flanges a' and the sole pressed back, the flanges pressed out and over the edges of the sole, and one hook c having been engaged with the outer shank-edge of the sole, the clamp C is sprung to throw the hooks c c apart. The sole then being pressed as far backward upon the boot as possible, the other hook c is sprung over the inner edge of the shank.

In addition to these features I apply a strap, D, to the rear ends of the flanges a', which strap, passing around the rear of the boot and being flexible or elastic, will serve to maintain an increased tension upon the flange a' and add to its clamping qualities.

Parts of the invention may be used without the whole.

I may omit either the strap D or the clamp C, or both, and still maintain the gist of the invention and the essential features of advantage thereof.

The flange may be made to clamp the sole sufficiently to hold the parts together without other aid.

Other modifications in details of construc-

tion may be made without departing from the principle or sacrificing the advantages of the invention, the essential elements of which are a portable sole with an elastic sole engaging flange.

5 What I claim as new is—

1. A detachable sole for foot-wear, having an elastic flange extending from the shank portion continuously along each side, and around the toe portion, the said flange being of a depth corresponding to that of the sole which it is to engage, and adapted to overhang the edge of the sole, whereby the sole will be held detachably to the boot or shoe by 15 the inherent spring of the flange, as set forth.

2. A detachable sole, as A, having a flange, a' , with bead a^2 , of elastic material, which normally inclines inwardly and is continuous upon the sides and around the front, and 20 which may be sprung over the edges of the sole of a boot or shoe, whereby the said sole will be held to the sole only of the boot or shoe by the inherent spring-clamping force of the flange without covering any portion of the 25 upper, as set forth.

3. A detachable sole, as A, having an elastic sole-engaging continuous flange, a' , with bead a^2 , made in a single piece, and having at its rear portion a spring-clamp, C, with shank-engaging hooks e , combined and operating as and for the purposes specified.

4. A detachable sole, as A, having an elastic sole-engaging flange, a' , combined with a strap, D, arranged to pass around the rear of the boot or shoe and to maintain a tension 35 upon the flange a' to increase its clamping-spring, as specified.

5. The detachable sole described, consisting of the roughened body A a , having elastic flange a' , with bead a^2 , the spring-clamp C, 40 having shank-engaging hooks e , and the strap D, for maintaining a tension on the flange, as specified.

In testimony whereof I affix my signature in presence of two witnesses.

MATTHEW HAWE.
